UNITED STATES PATENT OFFICE.

CHARLES H. PERKINS, OF PROVIDENCE, RHODE ISLAND.

HORSESHOE-MACHINE.

SPECIFICATION forming part of Letters Patent No. 340,350, dated April 20, 1886.

Application filed February 1, 1886. Serial No. 190,428. (No model.)

To all whom it may concern:

Be it known that I, CHARLES H. PERKINS, of the city and county of Providence, in the State of Rhode Island, have invented certain new and useful Improvements in Horseshoe-Machines; and I do hereby declare that the following specification, taken in connection with the drawings furnished and forming a part of the same, is a clear, true, and complete description of the several features of my invention.

In a cotemporaneous application for Letters Patent I have disclosed certain comprehensive features of invention, and have illustrated their application to various forms of horseshoe-machines.

My present application relates to certain features of invention which are limited to that general variety of machines which embody a series of shoe-forming dies continuously moved forwardly or in one direction upon and with a continuously-traveling bed, as distinguished from another equally well-known type of machines having a single forming die mounted upon and carried by a reciprocating bed, and it is to be understood that my said cotemporaneous application illustrates and describes a machine having such a series of dies, and also single-die machines, for the purpose of illustrating certain features of invention common to all of them.

After fully describing the mechanism illustrated, the features deemed novel will be specified in the several clauses of claims hereunto annexed.

Referring to the drawings, Figure 1 illustrates in perspective a machine embodying my invention. Fig. 2 is a side elevation of said machine. Fig. 3 is a vertical section of the frame and the upper portion of the machine; but it shows a revolving die-bed in side view. Fig. 4 is a central lateral vertical section of said machine. Fig. 5, in an enlarged plan view, illustrates certain swaging-dies in detail. Fig. 6 is a section of a portion of the machine shown in Fig. 5 on line x. Fig. 7 is a section on line y, Fig. 5. Fig. 8 is an enlarged side view of a portion of the revolving die-bed, and it also shows a portion of the frame of the machine in section. Fig. 9 is an enlarged plan view of a portion of the periph-

ery of the revolving bed, one of its forming-dies, a horseshoe thereon, and certain lever-jaws, by which the finishing bend is accomplished and by which the shoe is subsequently maintained in a clamped condition. Fig. 10 is a section of the parts shown in Fig. 9, on line z. Fig. 11 illustrates a portion of the die-bed near its periphery and a certain spreading device by which the said lever-jaws are moved from their forming-die. Fig. 12 illustrates in plan a portion of the periphery of the revolving bed, a forming-die, a horseshoe thereon, and it also shows in section the studs with which said forming-die co-operates for initially bending a blank. Fig. 13, in several views, illustrates a blank in the form preferred by me for use in this machine. Fig. 14, in several views, illustrates a blank after it has been swaged at its ends in this machine prior to the bending operation.

The frame A of the machine may be widely varied in form, so long as due provision is made for suitable bearings for the requisite movable parts and proper supports are afforded for such stationary parts as operate passively in connection with said movable parts of the machine. At the front upper portion of the frame there is an inclined table, a, upon and across the upper portion of which a straight blank is placed for delivery to the machine.

In machines heretofore designed with a view to relying upon a series of shoe-forming dies mounted on a bed which always carries the dies forward, or in one direction, for co-operating with bending and hammering mechanism in the manufacture of horseshoes, said beds have been either in the form of disks rotating on vertical axes and carrying the series of forming-dies on the upper side of the bed in a circular but horizontal path, or said beds have been composed of a series of rectangular die-blocks each having a forming-die thereon and all of them coupled together endwise, like the links of an endless chain, and mounted upon rag-wheel drums having horizontal axes. For obtaining the best results the series of forming-dies should be mounted on the periphery of a circular bed having a horizontal axis, and while the prime value of certain portions of my invention will accrue in the use of machines with die-beds so mount-

ed, substantially desirable results will be obtained by their use in either of the other two forms of machine referred to.

So far as my knowledge extends I am the first to devise a horseshoe-machine embodying a series of forming dies, which are always moved forwardly in one direction, in which a straight blank is first swaged at its ends for thickening the heels of a shoe before said forming-dies proceed to co-operate with devices for bending the blank. I am also the first to devise and employ such a series of shoe-forming dies in connection with hammering mechanism, and with a series of clamping-jaws, which in pairs firmly hold a bent blank at a forming-die, while said blank progressively undergoes the hammering operation. I am also the first to devise and employ such a series of shoe-forming dies, in connection with stationary studs, by which an initial bend is developed in the blank, and with a series of automatic lever-jaws or any equivalent devices, which, working in pairs, develop a finishing bend in the blank at the heels of the shoe and thereafter operate as clamping jaws, moving along with each die for so confining the bent blank that a hammer can properly operate thereon while on its way through the machine.

The blanks as preferred by me for use in this machine are of such contour as can be readily developed by rolling. They are also of proper length for one shoe, and have been previously creased and punched, as shown in Fig. 13.

In describing the machine shown I will sequentially refer to the bending mechanism, the hammer, and the swaging mechanism, instead of proceeding in the order of their successive operation upon a blank. The die bed B, as here shown, is a comparatively heavy wheel or disk, and is mounted upon a heavy horizontal axis or shaft, b, provided at one end with a suitable coupling, b', by means of which it can be connected to and driven by any suitable driver. The periphery of said bed is provided with any desired number of properly-projecting forming-dies, B', of which four are here shown, at regularly-spaced intervals. These forming dies are detachable from the bed, so as to admit of the use of dies of various sizes and of such various shapes as are incident to horse and mule shoes. In making an initial bend in a blank each of said forming-dies, moving continuously in one direction, successively co-operates with a pair of stationary pendent studs, c, at the upper front portion of the machine. Against the front of said studs a straight blank is properly placed, so that a forming-die will engage centrally with said blank, and then force its way with said blank between the studs, and thereby develop the initial or main bend. (Illustrated in detail, in connection with a blank, d, in Fig. 12.) The finishing bend consists in closing the two ends or heels of the blank inwardly against the sides of the form-

ing-die, near its rear, and this is accomplished by means of a pair of lever-jaws, e, as illustrated in connection with a bent blank, d, in Fig. 9. The lever-jaws are mounted upon and are carried by the die-bed, and each forming-die is provided with a pair thereof. In other words, one pair of stationary pendent studs, c, serves for all of the forming-dies consecutively; but these several pairs of lever jaws, after completing the bend, move forward with their forming-dies, and thereafter serve as clamps for properly controlling a bent blank during the succeeding hammering operation, to be hereinafter described. Each lever-jaw e is mounted upon the end of its own rock-shaft f, occupying a radial line on the side of said disk and mounted in bearings, within which it can freely move longitudinally, limited by a collar and screw, and be equally free to semi-rotate for swinging its working-face e' partially across the face of the die-bed toward and from the adjacent side of its forming-die, and also for enabling said working end or face to be swung free from the die-bed and to then drop below the peripheral line of the die-bed, so that it may then pass freely beneath the table a, and without contact with the pendent studs c or with other portions of the machine which would otherwise occupy its circular path. The outer end of each lever-jaw is provided with a friction roller, e², and with a shoe or bearing-block, e³, below said roller.

Near the top of the side plates of the frame A, on their inner sides and above the shaft of the die-bed, there are two stationary but adjustable segmental cam plates, e⁴, bolted to the frame and standing edgewise and parallel with the side of the bed, both plates being shown in top view in Fig. 9, and one in side view in dotted lines in Fig. 8. The front end of each cam-plate is inclined from its lower edge, so that as a forming-die approaches said cam-plates the shoes or bearing-blocks e³ engage with and ride up their inclined front edges, thus lifting the lever jaws to a point slightly above the periphery of the die-bed, and then the friction rollers e² strike against the flat vertical surface of the two other stationary plates, e⁴, which by their abutment with the rollers cause the working-faces e' of said jaws to swing into contact with the blank d, and thereby to finish the bend at the two heels of the horseshoe. These abutting plates e⁴ are of sufficient length to enable them to maintain reliable control over the jaws, so that they may then serve as clamps while the blank is passing beneath the hammer C. As the working-faces of these lever-jaws are much thinner than the already thickened heels of the bent blank, they cannot interfere with the proper operation of said hammer. After passing the hammer, the lever jaws are, on leaving the abutting plates, unconfined, and when they and their forming dies have been carried downward in their path the horseshoe is then free to drop from the bed, and as the jaws are brought around again and upward to

the front of the machine they are each engaged by a stationary finger, e^6 , which occupies a path between the pivot of the jaw and the forming-die, so that as the die-bed further 5 rotates, the working-face e' is swung backward clear of the bed, which leaves the jaw free to drop again, by gravity, as soon as its spindle approximates to a vertical position, as is clearly indicated in dotted lines beneath the table 10 to a in Fig. 8. For accelerating the retiring movement of said rock-shaft, a retractile spring, f' , may be employed, as is illustrated in Fig. 4, with one of said rock-shafts, and such springs will always be desirable if said rock-shafts are so mounted that gravity cannot be relied upon. The outward throw of the inner end 15 of each jaw will be effected independently of the spreading finger e^6 by providing each rock-shaft f with a torsional spring loosely encircling the shaft, as indicated at f^2 in Fig. 4; and it is obvious that the torsional and retractile action of both of the springs shown can be readily provided for in a single spring, and by coupling one end of such a spring with 20 the collar shown the latter and its screw will serve not only to limit the longitudinal movement of the rock-shaft, but also to adjust the torsional force of the spring.

The hammer C is located above the axle b 30 and across the face of the die-bed. In its best form it embodies a series of rollers, g , on pivots between two disks, g' , mounted on a shaft, g^2 , and provided with a pulley, g^3 ; and it is driven at high speed, so as to rapidly deliver 35 numerous blows or strokes upon a blank while the latter is slowly passing beneath it.

Fig. 4 illustrates the relative positions of the hammer, the lever-jaws, and the forming-die while a blank, d , is undergoing the hammering operation.

The swaging jaws or dies D are here located at the upper front portion of the machine, at the table a , and they must always be in front of the pendent studs e . Two of 45 said dies or jaws are employed, each having a detachable working-face, h , which co-operates with a coincident stationary face, h' , on a metal block, which is firmly but adjustably mounted on the frame of the machine. Each 50 swaging-die, considered as a whole, is in the form of a curved lever, and it is pivoted centrally, as at i , to the frame of the machine, and at its outer end it is coupled by a strong ball-and-socket bar or link, k , to the upper end of 55 a lever, k' , pivoted to the side of the frame, and provided below its pivot with a retractile spring, k^2 , which normally causes the face of the swaging-die to be fully retired from the face g' , with which it co-operates.

For operating said swaging-dies a cam, l , is 60 provided at each side of the machine on the shaft b for intermittently engaging with and vibrating the lower end of said lever, k' , and said cams are shaped substantially as shown in Fig. 2, so as to cause four vibrations of the 65 swaging-dies during each revolution of the die-bed, and said cams are so set upon their shaft

that said swaging-dies are operated at times next preceding the approach of each forming-die, so that as each of the latter arrives at the 70 table a it may be supplied with a properly swaged blank.

In Figs. 5 and 6 a blank, d , is shown, with one of the swaging dies operating thereon.

The general operation of the machine will 75 be fully apparent on reference to Fig. 13, which shows a blank, d , as prepared by me prior to use in this machine. In a similar manner Fig. 14 illustrates said blank after it has been swaged by the dies D . In Fig. 12 the blank 80 is shown after the initial bend has been developed; and Fig. 9 shows the same after the second or finishing bend has been completed.

The desirability of a centering-gage in this variety of machine is the same as in others 85 heretofore devised by me for securing shoe-heels of uniform length, and I employ the well-known form of pendent spring-gages m , as clearly shown in Figs. 1 and 2, said springs being of equal resiliency and so slender at 90 their lower ends as to not be in contact with the swaging-dies, and when a blank is dropped into place with its two ends abutting against said gages its middle must occupy a line coincident with the center of the approaching 95 forming-die B' .

In view of the specific description already given of the mode of operation of the several parts, it is believed to be unnecessary to describe the operation of such machines, considered as a whole, further than to say that the straight blanks are delivered by hand between the gages to the swaging-dies, and that the bending and hammering operations successively follow, the horseshoes being dropped 100 below the bed from each forming-die as soon as it assumes an inverted position. This free delivery of the shoes from the dies is of course dependent upon the fact that the forming-dies are consecutively reversed in position; but I 105 can rely upon a stationary forked clearer in proper relation to the path of the forming-dies and back of the hammer, as indicated in dotted lines in Fig. 2, there being a wedge-shaped foot on each leg of said clearer, which is interposed at one side of a horseshoe and between it and the bed, so as to lift the shoe and leave it free to drop into a chute or into a suitable receptacle. This clearer might also 115 be relied upon to perform the functions of the stationary fingers e^6 , before described; but a clearer may generally be dispensed with if the forming-dies be reversed in position during their movements, whether on the circular bed having a horizontal axis or on the endless-chain bed hereinbefore referred to.

It is now to be understood that while I prefer to employ a machine in its complete form, and substantially as illustrated, I am aware that for performing the bending operation 120 only, a machine embodying my invention has a value equal to or greater than any other known to me, in which case the hammer and the swaging-dies can be dispensed with or

left inactive, although said swaging-dies can always be used to good advantage; also that said machine can be profitably used purely as a hammering - machine, in which case the 5 swaging-dies can be dispensed with or left inactive, and the pendent bending-studs *c* may or may not be employed, because if a previously bent blank of proper form be applied to each forming-die as it reaches the table *a*, 10 said bent blank will be carried forward and so engaged by the lever-jaws that they will operate as clamps and properly present the shoe to the hammer and properly control it during the hammering operation.

15 I have hereinbefore indicated that it is not new in horseshoe-machines to employ a series of forming-dies which are always moved in one direction, and it is also to be understood that such machines have also embodied bending 20 mechanism which operated to impart the initial bend, substantially as in my machine, by means of each forming-die and a pair of stationary studs or their equivalent common to all of said dies. Some of said prior machines 25 have also embodied lever-jaws for making a finishing bend, but said prior jaws have also been relied upon for swaging and thickening the heels of a shoe while developing the finishing bend, whereas in my machines the lever-jaws do not swage but simply bend the 30 blank inward at the heels, the blank having been fully swaged at its ends before reaching the bending mechanism. Some of said prior continuously - traveling bed - machines have 35 been described in Letters Patent as having hammers intended to operate upon a bent blank while moving along upon and with a forming-die; but in no instance known to me prior to my present invention has a continuously- 40 traveling bed provided with a series of forming-dies been also provided with a pair of lever jaws for each forming-die, whether said lever-jaws were relied upon for bending alone or swaging alone or for performing both of 45 said operations, or which, in addition to performing either or both of said operations, further served as clamps for confining the bent blank in proper position during the succeeding hammering operation. In other words, 50 whether said prior machines have had a series of forming-dies on circular beds provided with horizontal axes or with vertical axes, or whether a series of die blocks coupled on the endless-chain principle served as the traveling bed, there has always been employed with such beds a single set of lever jaws or their equivalents for making an initial as well as a terminal or finishing bend; or said jaws were 55 relied upon for making said latter bend coupled with a thickening or swaging effect, so that each forming die of the series would successively co operate with the one pair of lever-jaws. In none of said prior machines are said jaws mounted upon and moved with the bed, 60 and hence they could not operate as clamps for so holding the blank at the die that the succeeding hammering operation could be practi- 65

cally and efficiently performed, and also so that the heels of the shoe could not spread, as would otherwise be an inevitable incident of hammering. It will in this connection be obvious that any devices heretofore relied upon for thickening the heels by swaging at the time of making the finishing bend, must have working-faces equal to or greater in height than the height or thickness of the heel desired, and that if swaging-jaws were thereafter relied upon for clamping the bent and swaged blank while passing beneath a hammer, the swaging-jaws would prevent the hammer from properly striking the rear portions of the shoe. 75

Having thus described my invention, I claim as new and desire to secure by Letters Patent—

1. In a horseshoe-machine, the combination, substantially as hereinbefore described, of the 85 series of forwardly-moving shoe-forming dies, the series of automatic lever-jaws carried in pairs with and adjacent to each forming die, and a hammer whereby bent blanks or shoes carried on said forming-dies may be successively presented to said hammer and properly clamped by said jaws during the hammering operation. 90

2. In a horseshoe-machine, the combination, substantially as hereinbefore described, of the 95 circular rotative die-bed having a horizontal axis, the series of forming-dies on the periphery of said bed, the series of automatic lever-jaws carried by said bed in pairs adjacent to each die and the rotary hammer. 100

3. In a horseshoe-machine, the combination, substantially as hereinbefore described, of the series of forwardly-moving shoe-forming dies, the series of automatic lever-jaws carried in pairs with and adjacent to each die, a pair of 105 stationary pendent studs common to all of said dies, and a hammer whereby a straight blank is partially bent by each of said dies and said pair of studs, a finishing bend developed by said automatic lever-jaws, and the 110 bent blank then delivered to the hammer and firmly clamped by said jaws during the hammering operation. 115

4. In a horseshoe-machine, the combination, substantially as hereinbefore described, of the 115 circular rotary bed on a horizontal axis, the series of shoe-forming dies on the periphery of said bed, the pair of stationary pendent studs, the series of automatic lever-jaws mounted on said bed in pairs adjacent to each die, 120 and the rotary hammer whereby a straight blank delivered to either of the dies will be initially and finally bent, then hammered, and then released from said die when inverted by the continued rotation of said bed. 125

5. In a horseshoe-machine, the combination, substantially as hereinbefore described, of a series of forwardly-moving shoe-forming dies, a series of automatic lever-jaws moving in pairs with and adjacent to each forming-die, 130 a hammer, a pair of swaging jaws or dies, and a pair of stationary bending-studs located between said swaging-jaws and the hammer, whereby a straight blank delivered to said

swaging-jaws will be thickened at its ends, then initially bent by some one of the forming-dies co-operating with said studs, then finally bent by the lever-jaws co-operating with said die, and then delivered to the hammer and be firmly held by said lever-jaws during the hammering operation.

6. In a horseshoe machine, the combination, substantially as hereinbefore described, of the circular rotative die-bed mounted on a horizontal axis, the series of shoe-forming dies on the periphery of said bed, the stationary bending-studs, the blank-swaging jaws in front of said studs, the series of automatic jaw-levers mounted in pairs on said bed adjacent to each forming-die, and the rotary hammer.

7. In a horseshoe-machine, the combination, substantially as hereinbefore described, of a series of forwardly-moving forming-dies, a pair of pendent studs common to all of said dies, and co-operating therewith for initially bending a blank, and a series of automatic jaw-levers moving in pairs with each of said forming-dies and co-operating therewith in completing the bend in a blank.

8. In a horseshoe-machine, the combination, substantially as hereinbefore described, of the circular rotary bed mounted upon a horizontal axis, a series of shoe-forming dies on the periphery of said bed, the pair of stationary studs co-operating with all of said dies for making initial bends in blanks, and the series of automatic lever-jaws mounted on said bed in pairs adjacent to each forming-die and co-operating therewith for making the finishing bend in each blank carried by said forming-die.

9. In a horseshoe-machine, the combination, substantially as hereinbefore described, of a series of forwardly-moving forming-dies, a pair of swaging-dies for thickening the ends of straight blanks, a pair of stationary studs at the rear of said swaging-dies for co-operating with all of said forming-dies in making initial bends in blanks, and a series of automatic lever-jaws moving in pairs with and adjacent to each forming-die for making the finishing bend in each blank.

10. In a horseshoe-machine, the combination, substantially as hereinbefore described, of the circular rotary bed on a horizontal axis, the series of shoe-forming dies on the

periphery of said bed, the stationary studs co-operating with all of said forming-dies, the pair of swaging-jaws in front of said studs, and the series of lever-jaws mounted on said bed in pairs adjacent to and co-operating with each of said forming-dies.

11. In a horseshoe-machine embodying a series of forwardly-moving shoe-forming dies, the combination, with each of said dies, of a pair of lever-jaws moving therewith and adjacent thereto, stationary cam-plates for lifting said lever-jaws from a depressed position, stationary abutting-plates for swinging said jaws into working relations with their forming-dies, and stationary fingers for thereafter engaging with the inner ends of said jaws for throwing them away from their forming-dies and permitting them to retire from their working positions.

12. In a horseshoe-machine, the combination, substantially as hereinbefore described, of the rotary bed on a horizontal axis, the series of shoe-forming dies on the periphery of said bed, the series of lever-jaws mounted in pairs on said bed adjacent to each forming-die, the longitudinally-reciprocating rock-shafts on which said jaws are mounted, the stationary cam-plates for lifting said jaws and their rock-shafts, the stationary abutting-plates for swinging said lever-jaws toward their dies, and the stationary fingers for engaging with the inner ends of said jaws for throwing them away from their forming-dies and permitting them to drop on arriving at a substantially upright and vertical position during the rotation of the bed.

13. In a horseshoe-machine, the combination, with a traveling shoe-forming die, of the pair of vertically-reciprocating lever-jaws moving therewith and mounted respectively on sliding rock-shafts, a stationary cam-plate for lifting each jaw and its shaft, stationary abutting-plates for swinging the inner ends of said jaws toward the die, and stationary fingers for thereafter throwing the inner ends of said jaws outwardly and permitting them to drop below the die.

CHARLES H. PERKINS.
